UNITED STATES PATENT OFFICE.

CHARLES B. McDONALD, OF CHICAGO, ILLINOIS.

CAN-TESTING MACHINE.

No. 812,224.

Specification of Letters Patent.

Patented Feb. 13, 1906.

Application filed September 11, 1905. Serial No. 277,922.

To all whom it may concern:

Be it known that I, CHARLES B. McDONALD, a citizen of the United States, residing at Chicago, in the county of Cook and State of Illinois, have invented certain new and useful Improvements in Can-Testing Machines, of which the following is a specification.

The machine of this invention has for its object to provide mechanism for automatically testing cans and sorting out any cans which may be defective by reason of punctures or leaks. This operation is performed without the necessity for immersing the cans in water as is ordinarily done and without the necessity for constant attention on the part of the operator, the entire function of testing and sorting the cans being performed automatically after the cans have been delivered to the machine.

The invention consists in the construction and arrangement of a plurality of sealing-heads, each one adapted to clamp and seal a can during one revolution of the machine and during the testing operation, and in the provision of pneumatically - operated plungers adapted to be actuated by a perfect can to allow the can to be discharged at a predetermined point and adapted to remain inactive when an imperfect can is inserted, thereby providing for the discharge of all leaky or otherwise imperfect cans at a different predetermined point, which arrangement provides for the proper separation of the cans.

The invention further consists in the method of contracting and retracting the clamping-rods for the insertion and discharge of the cans and in the provision of a series of cam-lugs positioned at suitable points to effect the different operations.

The invention consists, finally, in the features of construction and combination of parts hereinafter described and claimed.

In the drawings, Figure 1 is a side elevation of the entire machine fitted with four sealing-heads; Fig. 2, a sectional elevation of the same with the sealing-heads removed; Fig. 3, a top or plan view of the machine with the sealing-heads removed; Fig. 4, a plan view of one of the sealing-heads; Figs. 5 and 6, opposite side elevations of the sealing-head; Fig. 7, a longitudinal elevation of the sealing-head, and Fig. 8 a section taken on line 8-8 of Fig. 4.

The machine consists of a base-plate 1, having uprights or posts 2, which serve to support a circular plate 3, which forms a base

or table for the support of the operating mechanism. The table has mounted thereon a spider 4, consisting of a circular hub 5, having radiating arms 6, which terminate in a ring 7. (Best shown in Fig. 3.) The hub 5 is in the form of a ring which surrounds a bearing 8 in the form of a cone 9, which is carried upon and formed integrally with a circular base 10; having a flanged bottom 11, which rests upon and is supported by the table 3, as best shown in Fig. 2. The circular base portion 10 forms a shoulder 12 in conjunction with the tapered cone portion, and the cone terminates at its upper end in a screw-threaded stud 13. The cone serves as a bearing for a hub 14, which is provided with a tapered interior 15, coinciding with the taper of the cone-bearing, and the tapered interior at its divergent end terminates in a circular bore 16, leaving a shoulder 17, which allows the hub as a whole to fit closely around the stationary bearing.

The hub on its interior is formed to have an upper flange 18, which serves as a step or abutment for a cap 19, which is screwed onto the stud 13 and serves to prevent the ingress of dirt or grit into the bearing. The hub is further provided with an upper circular attaching-face 20 and a lower attaching-face 21, separated by means of a circular flange 22, as best shown in Fig. 2. The hub has secured thereto, near its lower end, a gear-wheel 23, which abuts against the circular flange and encircles the lower attaching-face of the hub, 90 and above the circular flange is secured a ring-shaped attaching-plate 24, to which the sealing-heads are secured and from which they radiate. The gear-wheel 23 is rotated by means of a pinion 25, carried by a shaft 95 26, to which rotation is imparted through the middle of intermeshing bevel-pinions 27 and 28, the latter of which is mounted upon a power-shaft 29, mounted within a journal-box 30, suitably located upon the bed-plate 100 of the machine.

The attaching-plate 24 has radiating therefrom a series of sealing-heads of any suitable number. For the purposes of illustration four sealing-heads only are shown, although the number can be increased to any desired extent. Each of the sealing-heads consists of a tubular shank 31, having at its attaching end an L-shaped bracket 32, consisting of a vertically - extending arm 33 and horizontally-extending arm 34, the latter of which is secured to the upper face of the ring-shaped

attaching-plate by means of a screw-bolt 35, and the shank has projecting from its end a nipple 36, which is adapted to enter into the end of an air-duct 37, formed in the attaching-plate and extending radially from the center thereof. An air-duct is provided for each of the sealing-heads, and each of the air-ducts coincides with an air-duct 38 in the hub, forming, in effect, a series of continuous 10 radially-arranged air-ducts, one for each of the sealing-heads. The air-ducts at their inner ends open in the same horizontal plane, and air is admitted to the ducts successively through a single air-duct 39, which opens 15 through the face of the cone-bearing on a line with the path of travel of the radially-extending air-ducts. Air is admitted to the duct 39 through a centrally-located pipe 40, which extends down through the supporting-20 table 3 and has connected therewith a flexible air-tube 41, leading to a suitable source of supply for compressed air.

The nipple 36, which enters into the periphery of the ring-shaped attaching-plate, 25 serves, in combination with the screw-bolt 35, to firmly position the sealing-head in place and allow it to extend out over the stationary ring-plate 7 without the necessity of providing other means of support. The shank 31 has therein a bore 42, which passes 30 through an inner sealing-plate 43, provided with a nipple 44, which is encircled by a rubber gasket 45, which serves as a sealing-ring. The shank 31 has formed thereon a circular 35 flange 46, into which is screw-threaded a tubular casing 47, having on its top a tubular extension 48 of less internal and external diameter than the casing 46, and through the end of the extension is entered a movable 40 stud 49, mounted at its lower end on a plate 50, beneath which is located a flexible diaphragm 51, which is actuated by means of compressed air admitted through a branch port 52, leading to the bore 42 in the shank 45 of the sealing-head.

The movable stud 49 is surrounded by a coil-spring 53, which holds it normally depressed, forcing down the diaphragm into firm contact with the floor of the diaphragm-chamber, but allowing the stud to be raised by the movement of the diaphragm. The stud 50 outwardly projects from the diaphragm-casing and terminates in a pin 54 of less diameter than the stud, leaving a conical or cam surface 55 at the end of the stud. The movable stud operates with a catch-finger 56, terminating in a head 57, having a conical end 58, which is held normally in contact with the bevel or cam surface 55 of the stud by means of a coil-spring 59. The catch-finger 60 is slidably mounted within a casing 60 and extends in diagonal relation to the shank of the sealing-head and when in forwardly-projected position is adapted to be thrust under 65 the head 61 of a plunger 62 for the purpose

of holding the plunger raised. The plunger stands in vertical position and is slidably mounted within a tubular shell 63 and is adapted either to fall by gravity or be depressed by the action of a coil-spring 64.

The inner sealing-plate 43 cooperates with an outer sealing-plate 65, each of which plates is kite-shaped, and the outer sealing-plate is movable with respect to the inner plate to clamp and hold a can 66 between the two plates. The inner plate, which is formed integrally with the shank on the sealing-head has inwardly extending therefrom a sleeve 67, which surrounds a reciprocating rod 68, upon which the outer sealing-plate is mounted and along which it can be adjusted and held in adjusted position by means of a jam-nut 69. Any rotation of the sealing-plate is prevented by the provision of a set-screw 70, which passes through a sleeve 71, outwardly 85 extending from the outer sealing-plate, and said set-screw is adapted to enter a groove 72 in the upper face of the reciprocating adjusting-rod. The rod at its inner end passes through a bearing-sleeve 73, outwardly extending from the shank and in alignment with the sleeve 67, and between the two sleeves is a collar 74, rigidly secured to the adjusting-rod by means of a set-screw 75, to which collar is pivoted a link 76, which latter 95 has pivoted thereto a bell-crank lever 77. The bell-crank lever is pivoted to a boss 78 on the end face of the shank 67, and the forward or free end of the bell-crank lever has mounted thereon a roller 79, by the movement of which the adjusting-rod can be reciprocated to vary the distance between the sealing-plates.

The ring-plate 7 has secured thereto at one side an outwardly-extending segmental-shaped plate 80, the face of which is at a vertical elevation to allow the roller 79 to clear the plate as the sealing-plate is revolving around the machine. As shown in Fig. 3, the plate 80 is provided with a discharge-cam 81, having a beveled inner face 82, which lies within the path of travel of the roller 79 and is adapted to throw the roller from the position indicated by a dotted circle *a* to the position indicated by the dotted circle *b*. This movement opens the sealing-plates and allows a can to be inserted between the sealing-plates when the sealing-head passed to a position beneath the end of a chute 83. As the can falls between the sealing-plates the roller (indicated by the dotted circle *c*) strikes a locking-cam 84, having a beveled outer face 85, and said roller is moved to the position indicated by the dotted circle *d*, which movement clamps the sealing-plates together and seals the open end of the can against the rubber gasket carried by the inner sealing-plate. The opening of the air-duct 39 in the hub is at a proper point to admit air to the sealing-head after the can has been clamped in place, 130

and if the can be without leaks it will be carried around the machine and discharged after one revolution by the action of the discharge-cam.

5 The ring-plate 7 has secured thereto near the side opposite to the segmental plate 80 a similar plate 86, the face of which is preferably on the same horizontal plane. The plate 86 has secured thereto a trip-lever 87, which 10 extends diagonally beneath the plate and is pivoted to the plate at its rear end by means of a pivot 88. The trip-lever at its forward end has an upwardly-projecting contact-head 89, which lies below the path of travel of the 15 plunger 62 when said plunger is raised, but which lies within the path of travel of the plunger (indicated by the dotted circle e) when the plunger is dropped. The trip-lever has connected and movable therewith a forwardly-tapered cam-finger 90, which normally occupies the position shown in full lines in Fig. 3, but which is adapted to be thrown into the position shown in dotted lines. When 20 in normal position, the roller 79 will pass outside of the cam-finger, but when thrown into the position shown in dotted lines the roller will be brought in contact with the inner or cam surface 91 of the cam-finger and the rod, actuated by the roller, will be moved to discharge a defective can at a different point 25 from that provided for the discharge of perfect cans. After the trip-lever has been thrown into abnormal position it is returned to normal position by the action of a spring 92 or other suitable mechanism. After the plunger has dropped it will be again raised into 30 position to allow for the forward projection of the catch-finger 56 by means of a cam 93, which is preferably located at a suitable point 35 so as to raise the plunger subsequent to the insertion and sealing of a can.

In use the cans are fed down the chute and fall in position and are clamped between the sealing-plates by the action of the locking-cam 84, which throws the roller from an inwardly-projected to an outwardly-projected 45 position, thereby moving the bell-crank lever 77 and the link 76, which actuates the reciprocating rod 68, carrying the outer or movable sealing-plate. Air is then admitted 50 through the bore 42 in the sealing-head to the interior of the can. If the can be in perfect condition, none of the air so admitted will escape through the can and a predetermined 55 pressure will be exerted against the diaphragm 51, which raises the stud 49, forcing the bevelled or cam surface 55 against the tapered end of the catch-finger 56 and thrusting said finger forward, so as to hold it beneath the 60 head 61 of the plunger 62. This action of the diaphragm serves to hold the plunger raised during the entire revolution of the sealing-head and can carried thereby and until the 65 can is discharged at the proper point by the action of the discharge-cam 82, which throws

the roller inwardly and thereby moves the reciprocating rod outwardly to release the can prior to the insertion of another can into the same head. The discharge of the can relieves the pressure upon the diaphragm, but ordinarily the plunger will remain raised during the short period of time necessary for the introduction and sealing of a new can. If, however, the plunger should fall during this period, it will be immediately raised by contact 70 with the cam 93, and the catch-finger will be projected into position to hold the plunger 75 from falling.

If a leaky can be introduced into the machine and the air admitted, the pressure 80 against the diaphragm will be insufficient to hold the stud 49 in raised position, but said stud will fall, allowing the retraction of the catch-finger and allowing the plunger to drop. When the plunger has dropped, its lowered 85 end will occupy a position which will bring it into contact with the outwardly-projecting head 89 of the trip-lever 87, as shown by the dotted circle e, and the contact of the projecting plunger will throw the trip-lever outwardly and with it the cam-finger 90, bringing the cam-surface 91 into the same relative 90 position with respect to the roller as the cam-surface 82, so that the defective can will be discharged at the proper point.

95 The operation of the device is entirely automatic and dispenses with the necessity for immersing the cans in a bath of water and subjecting them to the inspection of an attendant. The operation is continuous, a new can 100 being inserted immediately after a tested can has been discharged, and the arrangement is one which enables a large number of sealing-heads to be mounted and operated on the same machine.

105 It will be seen from the foregoing description that the can-testing machine of present invention is one by which cans may be tested very rapidly, and, the operation being automatic, no defective cans will be overlooked 110 by the carelessness or inability of the attendant, which is sometimes the case in can-testing machines of ordinary construction. At the same time the machine saves the labor of an attendant and delivers the cans dry and 115 ready for use.

120 Although the invention has been described with considerable particularity, it is not intended to limit the invention to precise mechanical details herein shown and described, as such details may be modified considerably without departing from the spirit of the invention.

125 What I regard as new, and desire to secure by Letters Patent, is—

1. In a can-testing machine, a sealing-head provided with a fixed sealing-plate and a relatively movable sealing-plate and provided with air-passages opening through the fixed sealing-plate for admitting pressure to a can 130

- held between the plates, a slidable rod upon which the movable sealing-plate is mounted, a mechanism for moving the slidable rod, a flexible diaphragm in communication with the air-passage through the sealing-head, a plunger, a catch-finger adapted to hold the plunger raised when the diaphragm is in one position and adapted to allow the plunger to fall when the diaphragm is in another position, a cam adapted to actuate the rod-moving mechanism to discharge perfect cans at a predetermined point, a trip-lever adapted to be contacted and thrown by the plunger when the latter is actuated by the leakage of air from an imperfect can, a cam movable with the trip-lever and adapted when moved to actuate the rod-moving mechanism to discharge an imperfect can at a predetermined point, substantially as described.
2. In a can-testing machine, the combination of a revolvable plate having a plurality of sealing-heads radially projecting therefrom, each of the sealing-heads having a fixed sealing-plate and a relatively movable sealing-plate for holding and sealing the cans between the plates, a slidable rod upon which the movable sealing-plate is mounted, mechanism for sliding the rod to lock and release the cans, a diaphragm adapted to be actuated by the pressure admitted to the cans, a plunger adapted to be held in one position when full pressure is exerted on the diaphragm, and adapted to be moved to a different position when the reduced pressure of a leaky can is exerted on the diaphragm, a trip-lever adapted to be contacted and thrown by the plunger when in one position, a cam-finger connected and movable with the trip-lever and adapted when moved to actuate the mechanism controlling the slidable rod to discharge one kind of cans at a predetermined point, and a cam adapted to actuate the mechanism controlling the slidable rod to discharge the other class of cans at a predetermined point, substantially as described.
3. In a can-testing machine, a sealing-head consisting of a fixed sealing-plate, a movable sealing-plate slidably mounted with respect to the fixed sealing-plate, an air-passage opening through the fixed sealing-plate and adapted to discharge compressed air into a can, a diaphragm in communication with the air-passage, a stud with a beveled end adapted to be raised and lowered by the movements of the diaphragm, a catch-finger provided with a beveled end adapted to abut against the beveled end of the stud, a plunger provided with a shoulder adapted to be engaged by the catch-finger to hold the plunger in raised position when pressure is exerted on the diaphragm to raise the stud and outwardly project the catch-finger, means actuated by the plunger when in lowered position for discharging imperfect cans at a predetermined point, and means for discharging perfect cans at a predetermined point, substantially as described.
4. In a can-testing machine, a sealing-head consisting of a fixed sealing-plate, a movable sealing-plate slidably mounted with respect to the fixed sealing-plate, an air-passage opening through the fixed sealing-plate and adapted to discharge compressed air into a can, a diaphragm in communication with the air-passage, a stud with a beveled end adapted to be raised and lowered by the movements of the diaphragm, a catch-finger provided with a beveled end adapted to abut against the beveled end of the stud, a plunger provided with a shoulder adapted to be engaged by the catch-finger to hold the plunger in raised position when pressure is exerted on the diaphragm to raise the stud and outwardly project the catch-finger, a lever for moving the movable sealing-plate, a cam for throwing the lever to discharge perfect cans at a predetermined point, a trip mechanism adapted to be actuated by the projected plunger to throw the lever and discharge imperfect cans at a different predetermined point, substantially as described.
5. In a can-testing machine, a sealing-head adapted to receive and pneumatically seal a can and provided with an air-passage for admitting compressed air to the interior of the can, a flexible diaphragm having one of its surfaces in direct communication with the air-passage leading to the can for normally causing pressure to act on one side only of the diaphragm for outwardly projecting the same, the pressure being equal within the can and against the diaphragm, mechanism actuated by a retraction of the diaphragm due to a decrease of pressure within the can and against the diaphragm for discharging an imperfect can at a predetermined point, means for holding the can against the sealing-head, and mechanism for discharging the perfect cans at a predetermined point, substantially as described.
6. In a can-testing machine, a sealing-head adapted to receive and pneumatically seal a can and provided with an air-passage for admitting compressed air to the interior of the can, a flexible diaphragm having one of its surfaces in direct communication with the air-passage leading to the can for normally causing pressure to act on one side only of the diaphragm for outwardly projecting the same, the pressure being equal within the can and against the diaphragm, a stud carried on the incompressible side of the diaphragm, and mechanism actuated by the fall of the stud due to the retraction of the diaphragm for discharging the imperfect cans at a predetermined point, means for holding the can against the sealing-head, and mechanism for discharging perfect cans at a predetermined point, substantially as described.
7. In a can-testing machine, a sealing-head

adapted to receive and pneumatically seal a can and provided with an air-passage for admitting compressed air to the interior of the can, a flexible diaphragm having one of its surfaces in direct communication with the air-passage leading to the can for normally causing pressure to act on one side only of the diaphragm for outwardly projecting the same, the pressure being equal within the can and 5 against the diaphragm, a stud resting upon the outer side of the diaphragm, a spring surrounding the stud and adapted to equalize the pressure on both sides of the diaphragm, and mechanism actuated by the retraction 10 of the stud for discharging the imperfect cans at a predetermined point, means for holding the can against the sealing-head, and mechanism for discharging the perfect cans at a predetermined point, substantially as de- 15 scribed.

8. In a can-testing machine, a sealing-head adapted to receive and pneumatically seal a can and provided with an air-passage leading to the interior of the can, a diaphragm having its inner face only in direct communication with the air-passage for receiving thereon a pressure equal to the pressure within the can, a plunger adapted to be actuated by movements of the diaphragm due to a decrease of pressure thereon caused by leakage 25 from the can, and mechanism actuated by the plunger for releasing an imperfect can at a predetermined point, means for holding the can against the sealing-head, and mechanism for releasing perfect cans at a different pre- 30 determined point, substantially as described. 35
